UNITED STATES PATENT OFFICE.

ANTHONY ARMBRUSTER, OF HOUSTON, TEXAS.

LAUNDRY ASSORTER.

Application filed November 2, 1925. Serial No. 66,262.

My invention relates to laundry assorting devices and has particular reference to the post upon which the laundry is placed and the snap hook which is employed in securing the clothes upon the chain, or other device upon which the clothes are placed.

It is an object of the invention to provide an improved post and attaching means thereon for a laundry securing device.

10 It is also an object to provide a snap hook to be employed upon the clothes securing means which may not easily become unsnapped in use and which will not engage with or tear the laundry. It is also desired 15 that the snap have means thereon to identify the bundle of laundry which is secured together by means of the chain, or other line employed.

In the drawing herewith, a preferred embodiment of the invention is disclosed. 20 Fig. 1 illustrates a front elevation of the laundry assorter, forming the subject of my invention, with the snap hook thereon shown partly in section. Fig. 2 is a side elevation of the upper end of the laundry assorting post. Fig. 3 is a transverse section on the line 3—3 of Fig. 1. Fig. 4 is a side elevation of the slide member of the snap hook, showing the manner in which it is 25 held when introduced over the end of the snap. Fig. 5 is a similar side elevation of the snap hook. Fig. 6 is a side elevation of the assembled snap hook. Like numerals of reference designate like parts in all the 30 views.

In assorting laundry it is common to tie the garments, having sleeves or other openings therein, in bundles before introducing them into the washing machine to be 35 washed. In so doing the chain or other line is inserted through the sleeve or leg of the garment and the ends of the line are then fastened together. In assembling the garments upon the line, I have devised a post 40 by means of which the line may be threaded through the opening in the garment. In Fig. 1 the construction of the post is shown. There is a tubular post 1 which is threaded at 2 at the lower end, so that it may be 45 secured within a base plate 3. Said plate may be secured to the floor, or to a bench or other support, as desired, by means of screws inserted through openings 4 therein.

The post is slotted upon one side, said 50 slot extending from a point spaced slightly

above the base to the upper head of the post, which is closed, as shown at 5, and rounded off to form a smooth surface to avoid engaging with or tearing the garments. Said head 5 is preferably made solid on the inside and a hook 6 is secured centrally of the head on the inside thereof within the slot, 60 said hook acting as a support for the chain, or other line employed in securing the clothes in bundles. As will be noted from 65 Figs. 1 and 2, the slot 7 in the side of the post is cut deeper at 8, adjacent the upper end, so as to allow easy access to the hook upon which the chain 9 is secured.

The chain 9 may be of any ordinary construction and it is contemplated that the end links thereof may be secured over the end of the hook 6, but the chain may be shortened, if desired, by securing any selected one of the links over the hook in an 70 obvious manner. The chain depends vertically downward from the hook within the post and the lower end is brought through the lower portion of the slot so that it may be reached when the bundle is assembled. 75

On the lower end of the chain, or other line which is employed, is a snap hook 10. The construction of this hook is an important feature of the invention. It comprises a short length of spring wire bent in the 80 form shown in Fig. 5. The forward end of the same is bent upwardly and recurved at 11 to form the hooked end of the snap hook. The other end is bent around, as shown at 12, on an arc of slightly larger diameter 85 than that of the hook. The end of the wire thus bent is curved outwardly to a slight extent so as to hold the forward end 13 thereof extending slightly away from the body 90 of the hook. The said end 13 is turned slightly outward to form a point 14 adapted to engage within the slide or shield 15, which co-operates therewith.

The shield 15 comprises a piece of sheet metal bent into an elongated oval shape, as 100 shown in Fig. 3. The upper central portion of the shield is formed with a notch 16 extending through the body of the metal to form an opening to receive the point 14, upon the spring member of the snap hook. 105

It is contemplated that the line, or chain 9, will be secured over the forwardly hooked end of the snap hook and moved to the opposite end 12, as shown in Fig. 5. The shield 15 will then be engaged over the 110

hooked end of the snap and the resilient member 13 will be depressed to allow the shield to be moved over the end 14 thereof to the position shown in Fig. 6. The opposite end of the chain may then be secured over the hooked end 11 of the snap and the shield moved forwardly toward the hooked end 11, until the point 14 of the resilient portion of the snap may be received within the notch or opening 16, as shown in Fig. 1. The hook will then be in locked position and there will be no points projecting therefrom so as to catch upon the garments being washed. The side of the shield member 15 may be stamped with a number, as shown in Fig. 4, to identify the garments secured upon the line 9. In this way the clothes may be secured together and introduced into the washing machine and when washed, may be again readily assorted and identified.

The advantages of this device over similar prior constructions lie in the manner in which the upper end of the post is formed so as to prevent engagement with the garments and thus prevent injury thereto, and also in the construction of the snap with which the opposite ends of the line may be secured together after the clothes have been placed thereon. The snap is simple in construction and it is believed absolutely proof against accidental detachments. It is also of advantage in that the clothes secured together by this means will not engage upon

or tear accidentally by coming in contact with the snap hook.

While I have shown the device as intended for use with laundry appliances, it is obvious that it is capable of other uses, and I do not wish to be limited to the use here shown and described.

What I claim as new and desire to protect by Letters Patent is:

1. In a device of the character described, an upright tubular post, a base thereon, a rounded upper head on said post, said post having a longitudinal slot on one side below said head, a hook on the interior of said post secured in the lower side of said head, a flexible line adapted to be secured to said hook, and a snap hook on one end of said line.

2. In a device of the character described, an upright tubular post, a supporting base for said post, a rounded head on the upper end of said post acting to close the same, there being a longitudinal slot in said post on one side thereof, a hook secured in said head and depending within said post, a flexible line adapted to be secured upon said hook and means upon one end of said line to detachably engage with the line at other points thereon.

In testimony whereof I hereunto affix my signature this 27th day of October, A. D. 1925.

ANTHONY ARMBRUSTER.
